UNITED STATES PATENT OFFICE.

ROBERT S. BROWN, OF NEW BRITAIN, CONNECTICUT, ASSIGNOR TO THE NEW BRITAIN MACHINE COMPANY, OF NEW BRITAIN, CONNECTICUT, A CORPORATION OF CONNECTICUT.

MACHINE FOR MORTISING PULLEYS.

1,007,180.

Specification of Letters Patent.

Patented Oct. 31, 1911.

Application filed June 2, 1906. Serial No. 319,878.

To all whom it may concern:

Be it known that I, ROBERT S. BROWN, a citizen of the United States, residing at New Britain, in the county of Hartford and State of Connecticut, have invented certain new and useful Improvements in Machines for Mortising Pulleys, of which the following is a specification.

This invention relates to mortising-machines many of the features of which are of general utilization in the art, although primarily designed for use in the manufacture of wood-pulleys.

It is of common knowledge that many efforts have been made to produce a nicely-balanced wood-pulley, and in one system of manufacture this has been attempted by first gluing together the segments of the rim, then boring the shell thus formed, and sawing it through in a manner to receive the spokes, said spokes being disposed flat-wise to the plane of rotation of the wheel, and, therefore, causing great air-resistance and a disposition of the timber in arms or spokes in a manner to afford the least strength. In another method of manufacture the arms or spokes are placed edge-wise to the plane of rotation of the pulley where they have the least air-resistance and afford great strength, and in this method the spokes have generally been placed in position while the process of gluing the segments is under way,—the arms or spokes being thus built together. In this method the pulley is completed, and the arms or spokes being in place will preclude the turning or boring of the inside of the rim, and, therefore, a perfectly balanced pulley will not be formed. Various other processes have been tried for manufacturing pulleys of the character described, but they have either been impracticable, or have been too expensive.

By the system of manufacture for which the present machine has been designed a pulley with a perfectly-balanced rim is produced, and this is accomplished by first boring the inner side of the rim, then chucking said rim on the mortising-machine and making the mortise for two or four sets of arms (more if desired) in said rim, subsequently sawing the rim apart for insertion of the tenons of the arms or spokes, and then turning the periphery truly concentric with the inner side of the rim. The improved

method of manufacture is not, however, claimed in the present application.

Among the objects of the present invention is the provision of improved indexing-mechanism which will control the position of the pulley-rim or blank in such a way that the number and location of the mortises made therein may be accurately regulated as desired.

Another object of the invention is the provision of improved feed-mechanism driven from the cutter-actuating spindle, and which is adapted to reduce the feeding-speed whenever the speed of the cutter-chain is also reduced by a slippage of the driving-belt due to undue resistance of said cutter-chain.

A further object of the invention is the provision of means for actuating the head in which the cutter-chain is mounted instead of the table for facing-purposes.

Other objects of the invention relate to various combinations of co-acting elements, and to details of improvement all of which will be hereinafter described.

In the accompanying drawings, Figure 1 is an end elevation of a mortising-machine involving my improvements. Fig. 2 is a side elevation of the machine looking in the direction of the arrow A. Fig. 3 is a front elevation of the upper portion of the machine, certain parts being omitted and others shown in section. Fig. 4 is a side elevation opposite to that shown in Fig. 2 certain parts being broken away and others shown in section. Fig. 5 is a side elevation of a pulley, showing the spoke or cross-bar. Fig. 6 is a partial section of the pulley. Fig. 7 is a plan view of the pulley, showing the mortises therein. Figs. 8, 9 and 10 combined, constitute a longitudinal vertical section of the machine, showing the feed-screw, the chuck, and means for actuating the chuck-jaws, etc. Fig. 11 is a sectional view illustrating the end of the lower shaft of the machine opposite to that shown in Fig. 1, showing a means of lubrication and other details hereinafter set forth. Fig. 11^a is a side elevation of the eccentric-bushing, shown in section in Fig. 11. Fig. 12 is a partial horizontal section taken on line 12, 12 of Fig. 2. Fig. 13 is a detail view of the chain-tension mechanism and parts carried thereby. Fig. 14 is a detail section of the same showing more clearly the parts in-

volved. Fig. 15 and Fig. 16 are detail views in edge elevation and plan, respectively, of the chain-bar. Fig. 17 is a detail in section of means for securing the chain-bar, head 5 or slide after it has been adjusted. Fig. 18 is a partial front elevation of the chuck, parts being in section. Fig. 19 is a detail view of one of the chuck-jaws. Figs. 20, 21 and 22 are detail views of the chip-breaker, Fig. 20 being in section on line 20—20 of Fig. 21. Fig. 23 is a bottom plan view of the indexing-mechanism parts being in section. Fig. 24 is a section taken on line 24—24 Fig. 23; and Fig. 25 is a section taken on line 25—25 of Fig. 23; Figs. 26 and 27 are, respectively, side and plan views of the chuck; Fig. 27^a is a diagram showing in profile the cam carried by the chuck and coöperating with the indexing-mechanism; Fig. 28 is a plan view of one of the chuck-jaws and its extension; Fig. 29 is a plan view of the chuck with the face-plate removed; Fig. 30 is a side elevation of the chuck-jaw and its extension, shown in Fig. 28; Fig. 31 is a partial front view showing the chain and chain-bar and the guard-rail and chip-breaker. Fig. 32 is a detail of parts of the mechanism for actuating the indexing-dog.

30 Like numerals designate similar parts throughout the several views.

Referring to the drawings, the numeral 1 designates the frame of the machine, which may be of any desired type and is illustrated as a column rising from a base 2, and having bolted to its top a head 3 provided with a laterally extending arm 4.

In adjustable bearings 5 of the frame or column 1 is mounted a driving-shaft 6, provided at one end with fast and loose belt-pulleys 7 and 8, the belt being adapted to be shifted by the usual shipper 9 of any approved form, and rod-and-lever mechanism 9'—9² connected thereto. (See Figs. 1 and 3.) Rigid with the shaft 6 is a large pulley 10 over which passes a belt 11, while loose on the shaft 6 is a stepped cone-pulley 12 driven by a belt 13 in a manner herein-after described. In engagement with a pulley 14 constituting part of the cone-pulley 12 is a crossed belt 15, while rigid with the shaft 6 at the side opposite the cone-pulley 12 is a belt-pulley 16 over which a straight belt 17 passes.

55 In adjustable bearings 18 in the base 2 of the machine is journaled a driven shaft 19, said shaft carrying loosely-mounted thereon a pulley 20, over which the straight belt 17 passes, and a loose pulley 21, which is driven by the crossed-belt 15. A clutch 22 of any approved kind is splined to the shaft 19, and is actuated by a yoke 23 projecting from a rock-shaft 24 journaled in the base, said rock-shaft having a lateral arm 25 on its opposite end by which it is operated in a

manner hereinafter described, and said arm 25 having a head 25' for a purpose herein-after stated.

At one end the shaft 19 projects into a chamber 26 of the base 2 containing lubricant (see Fig. 11), and is journaled in an eccentric bushing 27 having a flange 27' provided with sockets 28 in which a tool may be inserted for turning said bushing. A spiral gear 29 is splined to the shaft 19 and it enters the lubricant 30 as said shaft rotates, and a ball-bearing 31 is located intermediate said worm and the inner end of the bushing. A lubricant-conveying chain 32 is mounted in a groove of the shaft 19, and the extreme end of said shaft bears against a grooved thrust-block 33.

Designated by 34 is a shaft, stepped upon a ball-bearing 35 which is supported upon a bracket 35' between the hub of said bracket and the hub of the spiral-gear 36, secured to the shaft 34 and with which the spiral-gear 29 engages. Said shaft 34 passes through the hub of bracket 35' and on its end is threaded to receive a nut 35² to prevent vertical displacement thereof. A covering-plate 37 is bolted to the open side of the chamber 26 and carries a valve or faucet 38 for drawing off the contents of said chamber (see Fig. 7). A screw 39 is inserted through the wall of chamber 26 and the point of the screw enters a V-shaped groove 40 in the hub of the eccentric bushing 27.

Referring to Fig. 8, in the top of the chamber 26 is an opening 41 closed by a cover 42, and through this opening lubricant may be supplied to said chamber. A screw 43 is fitted in a groove 44 of the column 1, being journaled at its upper end in an overhang 45 of said column, and is rigid with the shaft 34 at its lower extremity, said screw engaging a nut 46 carried by a slide 47 gibbed to ways 48 and 49 of the column, and said column being longitudinally grooved as stated (Fig. 8) to permit travel of the nut. Slide 47 is provided with a way 50 and has a chamber 51, and on this way is fitted for transverse adjustment a slide 52 gibbed to said way, as illustrated in Fig. 8, said slide 52 having a tubular hub 53. For adjusting the slide 52 any desired means may be employed, and shown for this purpose are a rack 54 secured to slide 47 and a pinion 55' rigid with a tubular shaft 55. Fitted for rotary movement on the slide 52 is a chuck face-plate 56, gibs 57 securing it in place, and said face-plate having a series of radial slots 58 for the reception of the bases 59 of chuck-jaws 60 projecting laterally from said slides, as shown in Fig. 18.

From what has been stated it will be manifest that the chuck has a movement up and down on the frame or column 1, and that it may be shifted from left to right to place

the pulley-rim in a new position for enlarging a mortise already made by a second cut of the chain hereinafter described,—this right and left movement being produced by the rack and pinion set forth, and said movement being limited at either side by adjustable set-screws 61 carried by brackets 62 rigid with the slide 47,—said set-screws being illustrated in Figs. 3, 26 and 29. In the outer face of the slide 52 are sockets 63 disposed in the illustrations given quartering about the circular periphery of the slide upon which the chuck-face-plate 56 is secured by the gibs 57, as before stated. Secured to the chuck-face-plate 56 in Figs. 8 and 18 is an arm 64, said arm having at its inner end a series of projections 65, through which screw-bolts 66 pass. This arm is of a shape in cross-section shown in Fig. 18, and is provided at one end with a longitudinal bore 67 for the reception of a sliding rod 68 having a manipulating knob 69 at its outer end and a locking-dog 70 at its inner end, said locking-dog being adapted to fit in any of the sockets of the slide 52, and to thus lock said slide and chuck-face-plate together, after an indexing movement has taken place, as will be hereinafter described. Between a collar 71 on rod 68 and bushing 72 threaded into the arm 64 is mounted a coiled spring 73, the function of which is normally to propel the rod and its locking-dog 70 inward, and, therefore, to cause the chuck face-plate to be locked to the slide 52. In another longitudinal bore of the arm 64 is mounted a tubular shaft 74 having a hand-wheel 75 at its outer end, and a beveled gear 76, rigid with its inner extremity, said bevel-gear being located in a bore 77 of the hub of the chuck-face-plate, and said gear intermeshing with pinions 78 (see Fig. 27) rigid with the screws 78' for actuating the chuck-jaw-slides 59, and thereby simultaneously shifting said slides either toward or from the axis of the chuck-face-plate.

Mounted within the tubular shaft 74 is another tubular shaft 55 carrying the pinion 55' heretofore described at its inner end and provided with a hand-wheel 80 at its outer end, thereby affording means for adjusting the slide 52 transversely of the slide 47, the limit of adjustment being regulated in either direction by set-screws 61 heretofore described. Mounted in the tubular shaft 55 is a pull-rod 81 provided at its inner end with an enlargement terminating in a cone-plug 82 which normally rests within a centering socket 83 in the slide 47, as illustrated in Fig. 8. A button 84 is secured to the outer end of the rod 81, and a spiral-spring 85 is located between a collar 86 on the rod, and the inner end of the bore in the tubular shaft 55, said spring serving normally to advance the pull-rod, illustrated in Fig. 8,

and thus to lock the chuck in a central position.

At its inner end the hub of the chuck face-plate 56 has rigid with its surface a cam 87, and coöperating with said cam is a roller 88 journaled in an arm 89 secured to a rock-shaft 90 mounted in a bracket 91 and in the slide 52. Upon this rock-shaft 90 (see Figs. 1, 2, 3 and 32) is splined the hub 92 of an arm 93, said arm having an internally-threaded socket adapted to receive the threaded shank 95 of a ball constituting one member of a universal joint, said ball being fitted within socket 97 carried by the rod 98, equipped at its upper end with a socket 99 receiving the ball which is rigid with the rod 101, and, therefore, constituting another universal joint. On the reverse end of the rod 101 is a grooved sector 101' adjusted in the larger sector 102, said sector 101' being splined upon the index-controlling-rod 103. A bracket 104 having a vertical arm is bolted to a flange of the slide 47 and this bracket is provided at its upper end with a head 105 provided with perforated ears 106—106' for the reception of the rods 103 and 110. A sliding connection is established between the sector 102 and rod 103 by a spline and feather as illustrated in Figs. 3 and 32. At its lower end the rod 103 is provided with a bifurcated block 103', said block being perforated to receive the lower end of the rod passing through an arm 107, said arm being positioned between the ears of the bifurcated block and projecting from a shipper-dog 108, secured by a screw 109 to a rod 110. At its inner end this shipper-dog 108 is of yoke-shape, and in the arms 111, 111' of the yoke are fitted adjustable stops 112, 112' equipped with nuts 113, 113' by which they may be adjusted, said stops being located opposite the head 25' of the arm 25, secured to the rock-shaft 24 above described.

Designated by 114 is a treadle pivoted on a shaft 115 journaled in a bracket 116 of the base 2, and this treadle is connected in any desired manner to the rod 110. A collar 117 is secured to the rod 110, and surrounding said rod between said collar and a perforated bracket 118 projecting from the base 2 is a coiled spring 120. This rod 110 passes through the head of the bracket 104 projecting from the slide 47, and enters at its upper end the perforated arm 121 of a bracket 122 rigid with the overhanging arm 4 of the head 3.

A stop 123 is adjustably secured by a screw 124 actuated by a sliding handle 125 to the rod 110 below its upper end, and another stop 126 is adjustably connected to said rod by a screw 127, operated by a sliding-handle 128 at a point on said rod beneath the head 105 of bracket 104. (See Figs. 2 and 3.)

As illustrated in Fig. 2 a coiled spring 129 is connected at one end to a pin 130 of the rocking-rod 103, and at its opposite extremity to a stud 131 of the head 3. Adjacent to its upper end the rod 103 passes through a bearing 132' of the bracket 132 projecting from the arm 4 and above said bearing said rod is provided with a locking-head or dog 133 consisting of two separated arms 133', 133² (see Figs. 23, 24 and 25) coöperating with an index-plate 134 hereinafter described. A perforated plunger bracket 135 (see Figs. 25 and 23) is secured to the top of the arm 4 by screws 136, and through the perforation in said bracket passes a plunger 137 swiveled upon a bolt 138 passing through ears 139 of a lever 140 pivoted at 141 to the side of the arm 2, as illustrated in Fig. 4.

Referring to Figs. 2, 3, and 12, designated by 142 is a rod to which the lever 140 is pivoted at 140', said rod passing through a bracket 143 bolted to bracket-arm 144 secured to the outer end of arm 4, and depending below said arm. Stud-shafts 145 and 146 project from the depending part 144' of said plate, and on the stud-shaft 145 is loosely mounted a gear-wheel 147, carrying rigid with its outer face a disk 148 provided with a series of slots or grooves 149, each open at its outer end. Sleeved on the stud-shaft 146 is a wheel 150 to the hub 151 of which is secured a manipulating-wheel or disk 152 having handles 153, and in the inner side of said wheel 152 is formed an oblong cam-groove 154, shown by dotted lines in Fig. 3. At its lower end the rod 142 is flattened at 142' and in said flattened portion is formed a slot 142² which fits over the stud-shaft 145, a nut 155 on said shaft securing it in place, and a washer 156 also on the stud-shaft, separating said flattened portion of the rod from the disk 148. Adjacent to its lower extremity the flattened portion 142' is provided with a roller-stud 157 which enters the cam-groove 154. Pins 150' extend inward from the wheel 150 and are adapted to enter the slots 149 in the disk 148 when said wheel is turned.

Designated by 158 is a slip-gear mounted on the hub 159' (see Fig. 12) of a disk 159 secured to the end of a shaft 160, said disk having curved slots 159² through which screw-bolts 161 pass to engage the gear 158, the function of said slip-gear being to change the relation between the hand-wheel 152 and the movable head carrying the mortising mechanism, as will hereinafter appear. A screw 163 is formed on shaft 160, said screw passing through the arm 4, and engaging a nut 164 rigid with a cutter-carrying head or carriage 165 movable in a guide-way 166 of the head 3 of the column and the arm 4. See Figs. 5 and 12. Carried by 65 this head and journaled in a bearing-bracket

167 thereof is a sliding shaft 168, provided with longitudinal grooves 169 which receive splines or feathers 170 from a bushing 171 secured by screws 172 or otherwise, to a comparatively wide, flanged belt-pulley 173.

Designated by 174 is a sleeve or bushing fixedly secured in a bearing 175 of the machine-top by screws 176 the pulley being bushed at 177 to rotate on said sleeve and being prevented from displacement longitudinally by a flange 178 on the sleeve 174 and the end of the bearing 175. To the bearing 175 is secured a fixed collar 179 fitted against the right hand end of said bearing, and projecting from said collar is a shield 174', provided at its end with a closure or knob 180, for the shaft 168. On the extreme inner end of the shaft 168 are fixed a sprocket-wheel 181 (see Figs. 12 and 14) and a collar 182, and between said collar and a reduced end of the bearing 167 is secured to said bearing by screws 183' a fan-case 183 for the reception of a suction-fan 184 of usual construction rigid with the shaft 168. A hood 185 hinged to the fan-case at 185' surrounds the end of the shaft 168, said hood communicating with said fan-case in the usual manner.

An endless cutter-chain 186 is driven by the sprocket-wheel, and passes over rollers 187 and 188 (see Figs. 15 and 16) journaled on roller-bearings 189 in the lower end of a chain-bar 190, said chain-bar being secured at its upper end to an adjustable block 191 by screws 192. Depending from the bearing-bracket 167 (see Figs. 14 and 17) is a grooved hanger 193, and in a socket of the block 191 is fitted a shank of a T-headed bolt 194, the head 194' of which fits in a groove 195 of said hanger. In this bolt is formed a conical depression 195' for the reception of the conical end 196 of a screw 197 threaded into the block 191, and having a finger-grasp or hand-wheel 198, said bolt serving to lock the block to the hanger after it has been adjusted. In a lateral extension 199' of arm 199 rising from the bearing 167 of head 165 is journaled a screw 200 having a hand-wheel 201, and below said hand-wheel a bevel-gear 202, the thread of said screw engaging a socket in a cross-section 203 connecting standards 204 rising from the block 191 so that said block 191 may be raised and lowered on the head and then secured in place by the screw 197.

Journaled in bearings 205, 206 (see Figs. 3 and 4) of laterally-projecting arms 205'-199 of the head is an inclined shaft 207 carrying a bevel-gear 208 at its upper end and a hand-wheel 209 at its lower extremity, whereby the screw 200 and the block 191 may be actuated to regulate the tension of the cutter-chain either by the wheel 201 or the wheel 209, the latter owing

to the height of the machine being brought down within convenient reach of the operator.

Laterally extending from the slide-block 191—one at each side thereof, are arms 210, 211, each having a head 210'—211', respectively, perforated to receive devices herein-after described. Sliding in the perforated head 210' (see Fig. 31) is a guard-rod or bar 214, while in the opposing head 211' of arm 211 is fitted for sliding movement a rod 215 of a chip-breaker-head 216 secured to the end of said rod by a screw 217. These rods 214, and 215 are connected by a curved 15 yoke 218 having perforated hubs 219 through which said rods pass, and in which they are adjustably secured by screws 220, one of which is shown in Fig. 13.

From the yoke projects an arm or table 221, and on the rod 215 of the chip-breaker, above said table, are sleeved weights 222 which may vary in number and normally tend to force the yoke and its attached rods downward to cause the chip-breaker to bear 25 against the work under yielding pressure, as set forth in my Patent No. 673,378 dated May 7, 1901, to which reference may be had.

Referring to Figs. 20, 21, and 22 it will be seen that the head or block 216 is provided 30 with a socket 216' in which the end of rod 215 is secured by a pin 223², and is also provided with a rectangular opening 216² for the reception of the chip-breaker proper 223 which comprises a bar of wood or other suitable material inclined at its inner end at 35 223' to rest upon the work adjacent to the mortise being formed and prevent the upper edge of said mortise from being damaged by splintering or breaking adjacent to the 40 upper run of the cutter-chain. In the opening 216² of the head 216 is placed an inwardly-flanged metal bar 224 from the forward end of which projects a chute 225 for receiving the shower of chips or cutting 45 re moved by the cutter-chain and directing them toward the hood 185 of the fan-case 183. This bar merges at its lower end into the chute 225 for which it constitutes a reinforce, its side 224' bears on the outer 50 surface against the wall of the opening 216², and on its inner surface against the bar or stock 223, and its flange 224² is located intermediate the top of the stick and the upper 55 wall of the opening 216². Threaded into the block 216 is a screw 217 having a knurled head 227, and by turning said screw its inner surface may be made to bear against the bar 224 and thus force the stick 223 laterally 60 against the wall of the opening in which it is placed to clamp it firmly in position, in virtue of which the screw will bear upon said metallic arm instead of directly against the stick as in the old constructions. By loosening the screw the chip-breaker may be read- 65 ily adjusted back and forth, and as the end

of the screw is always forced against a metallic part of the fixture no damage can be done to the wood of the stick.

As heretofore stated the belt 11 from the pulley 10 of the shaft 6 actuates the pulley 173, and on the inner end of said pulley 173 is a small stepped pulley 173' for driving the belt 13 and stepped pulley 12 loose on said shaft 6. As has also been stated a crossed belt 15 is driven from the element 14 of the 70 loose pulley 12 and drives a pulley 21 loose on shaft 19 journaled in the base 2, while a pulley 16 rigid with said shaft 6 operates a straight belt 17, and, through said belt, a pulley 20 loose on said shaft 19,—said pulleys 20 and 21 being alternately connected to the shaft by the clutch 22, or permitted idly to rotate thereon when the clutch is thrown to a neutral position. It, therefore, appears that the shaft 19 is driven in the feed direction by belting operated from the shaft 168 which drives the cutter-chain, and as said shaft 19 actuates the spiral-gearing described the screw 43 is also operated either to advance or withdraw the slide 47. 90

With the use of slight chain-bars in making small mortises, it has been found in practice that through over feeding of the work-support, the encountering of a knot or other unusual resistance, or the employment 95 of a dull cutter-chain, there is a tendency to force the feed more rapidly than the cutter-chain can stand, and, hence, the chain-bar will spring or wobble and an imperfect mortise will be formed,—this condition being 100 aggravated when the main driving belt supplying power to the cutter-actuating shaft slips, while the feed-mechanism driven from another source keeps in motion. In the present construction the feed-mechanism is 105 driven by belting from the cutter-driving shaft or spindle, and, hence, the feeding-speed will be reduced whenever, due to the unusual conditions specified the speed of the cutter-chain is reduced. In other words, by 110 controlling the speed of the feed-mechanism by the speed of the cutter-driving shaft a proportionate relation is always maintained between the two, so that said cutter driving-shaft will always be effective in driving the 115 shaft 19 of the speed-mechanism in a manner entirely to avoid all of the above-noted objections.

Designated by 227 (Figs. 28 and 30) are extension chuck-jaws, each comprising a 120 base 228 having a perforated bracket 229 depending therefrom through which the screw 78' passes and acts as a guide for said extension-jaw. A bolt 230 secures said extension-jaw to the main jaw 60 at a point 125 about in line with the top of the slide 59, and each extension-jaw is reinforced and channeled at 231 to receive its slide 59, and is provided at its outer end with a serrated face 232 having at its lower end a lip or 130

flange 232' against which the edge of the pulley-rim rests. Stop-screws or pins 233 (Fig. 18) prevent the chuck-jaw-slides 59 from running off their actuating screws 5 when spread to the full limit of their movement. In each end of the slide 47 a V-shaped recess 47' is formed, leaving intermediate each recess an arm 62' of the slide 47, each carrying the bracket 62 for the stop-screws 61. (See Fig. 29.)

Reverting to the indexing-mechanism (see Figs. 23, 24 and 25) a protecting cover 234 is secured to the plate 134, and adjacent to the inner edge of said plate is a line of 15 perforations 235 and a longitudinal slot 236 for the reception of a sliding bar 237, having a knob 238 by which it may be manipulated to cut out the desired number of perforations as illustrated in Fig. 23. Plate 20 134 and its hood or cover are adjustably secured to the slide 165 by bolts 239 passing through slots 240 in the plate. A longitudinal slot 241 is formed in the index-plate 134, and in each edge of said slot are concave 25 seats or depressions 242 and 243, the pairs of which are separated by projections 244 on one edge and 245 on the opposite edge, the seats and projections being located in opposing pairs diagonally opposite each 30 other. In the slot is located the reduced part 133³ of the indexing-dog 133, the projections 133' and 133² of which being, when the rod 103 is in the position shown in Figs. 24 and 25 above and below the indexing-35 plate.

Pulleys of the kind to be mortised in this machine are composed of plies of wood glued together in a manner to break joints around the circumference of the rim, these 40 plies in the illustration Figs. 5, 6 and 7 being indicated in a nine-ply pulley by the letters *a*, *b*, *c*, *d*, *e*, *f*, *g*, *h*, and *i*, although said pulleys may be of any desired diameter and may be composed of any required 45 number of plies.

Referring to Figs. 4, 6, 7 and 31 the pulley-rim to be mortised is illustrated, and is indicated by the numeral 246, the plies being marked by the letters *a*, *b*, etc., above set 50 forth. After the pulley-rim has been mortised at points directly opposite each other in each alternate ply as at *j*, *k*, *l* and *m* in the illustration given, it is sawed apart on the line 247 for the reception of the tenons 55 248 of the spokes, kerfs or slots 249 separating each pair of tenons, and serving to permit free passage of air. Each half-spoke 250 is provided with a pair of separated perforations 251, on each side of the half-groove 60 252 of the spoke-section for the reception of bolts 253 for securing the halves together to form the complete pulley, the bolts carrying nuts 254 at each end which bear against washers 355 and wood strips 356 beneath 65 said washers.

When the tenons 248 of each spoke-section have been glued in their mortises, the halves of the pulley are placed together, and firmly clamped in place by the bolts and nuts described, the result being a perfectly-balanced pulley the spoke or spokes of which are of a construction to afford the maximum of strength and the least air-resistance when the pulley is in use. While but one spoke is shown any suitable number of spokes crossing each other may be employed if desired, the ends thereof being mortised into different plies of the pulley. For instance if two spokes or arms were employed they would preferably cross at right angles, their tenons extending into alternate plies. Thus if a second arm were to be added to the pulley shown, its tenons would be mortised into plies *c*, *e*, and *g*. In a case of this kind it is apparent that circumferentially adjacent 75 mortises occur in alternate plies and it is to insure this disposition of said mortises that certain features about to be described are associated with the indexing mechanism.

Shown in section in Fig. 8 and projected to show the profile in Fig. 27^a is the cam 87 which as the chuck is rotated by hand 80 controls the movement of the indexing-mechanism, the face of said cam being in contact with the roller 88 carried by the 85 arm 89 pinned to the shaft 90 as stated. Referring to said Fig. 27^a this cam is equally divided into two high and two low portions separated by inclined surfaces as 87', 87², 87³, 87⁴, and 87⁵ thus making the changes 90 100 105 110 115 120 10080 10085 10090 10095

tering mortises for a two arm pulley, the cam-roller will be moved to its extreme relative position thereby shifting the head 133 to coöperate with the opposite series of notches in the index plate 134 which will so affect the positioning of head 165 as to bring the circumferentially adjacent mortises in alternate plies.

In the operation of the machine a pulley-
10 rim 246 is placed upon the chuck-jaws 60 or the extensions of said jaws 227, as determined by the diameter of said rim, and the wheel 152 is then turned to actuate the screw 163 through interposed mechanism
15 and adjust the sliding head 165 to the proper position to bring the cutter-chain 186 and chain-bar 190 to a point opposite the ply in which the first mortise is to be formed. If a fixed relation existed between the gears 147
20 and 158 there would be no certainty that the step by step movement imparted to the head 165 by the mechanism described, would bring the cutter-chain into exact alinement with the desired ply, but the adjustability of gear
25 158, obviously provides means whereby the proper relation to secure the desired alinement may be readily obtained. As soon as the head is positioned by the wheel 150 whose pins enter the slots 149 in disk 148, the rod
30 142 is actuated by the cam 154 of wheel 152 thereby pulling down the outer end of the pivoted lever 140, and causing the pin 137 at its opposite extremity to enter the perforation 235 then opposite said pin, and to lock
35 the parts in place. When this operation has been properly carried out and the pulley-rim is in correct position the treadle 114 can be depressed, to pull down the rod 110, the shipper dog 108, and the rod 103.
40 If the indexing-plate 134 carried by the sliding head has been brought to the correct place the arms 133¹ 133² of head 133 will occupy the position illustrated in Figs. 23 and 24, and will pass freely through the
45 slot 241 and the groove 243, and thus will not impede the downward movement of the rod 103, but if said arm should be in a wrong position a block will occur and the treadle can not depress said rod to shift the
50 clutch and start the feed-mechanism in action. Assuming the parts to be in correct position the treadle will be depressed and through the connections described will pull down the rods 103, 110, rock the shaft 24 and shift the clutch 22 into engagement with the pulley 21, and the crossed belt 15, actuated by the means described from the cutter driving-spindle 168, will now rotate the shaft 19 and the spiral gear 29 of said shaft will
55 rotate the spiral gear 36 which actuates the screw 43, thereby imparting an upward movement to the slide 47 and forcing the pulley-rim 246 into contact with the cutter-chain 186, thus forming a mortise in the
60 ply b of said pulley, as illustrated in Fig.
65

31, the presser-foot or chip-breaker being in contact with said ply at this time and performing their usual functions until said mortise is completed. As the slide 47 moves upward it carries with it the bracket 104, 70 and when the head 105 of said bracket engages the adjustable stop 123 of rod 110 it will raise said rod, and through the shipper-dog 108, ship the clutch to a neutral position to stop the feed after which said clutch may be manually or otherwise suitably operated to reverse the feed so as to lower the work away from the cutter chain. As the rod 110 is elevated the rod 103 moves with it and the head 133 moves through the indexing-plate 134 and will release said plate for a further indexing-movement of the tool-head to bring it into position for forming a mortise in the alternate ply d of the pulley-rim. By rotating the wheel 152 the mechanism associated therewith is actuated to rotate the screw 163 sufficiently to bring the sliding head, its cutter-chain and chain-bar to a position opposite the ply d above mentioned of the pulley-rim, and if this position is a correct one the treadle may again be depressed to repeat the operation, and so on until the four mortises are formed in the upper part of the pulley-rim,—each mortise being made in an alternate ply of said pulley-rim as stated. 90
95

After a series of mortises suitable for the pulley-rim being acted upon has been formed it becomes necessary to rotate the chuck and the pulley thereon one-half turn 100 or in other words to bring a new part of the pulley directly opposite said mortises in position for an exact replica of the operations already performed. To accomplish this the knob 69 is grasped and the rod 68 is pulled outward to release the locking-dog 70 from the slot or groove 63 in the manner stated, and said rod will remain in a withdrawn position while the chuck and pulley are rotated about the circumferential periphery of the slide 52 sufficiently far to bring the other part of the pulley into position for correct mortising-operation. When said rod is released the spring 73 will immediately force it forward to cause the locking-dog again to engage a slot or groove 63 of the part 52. During the rotation of the chuck to effect this changed position of the pulley the cam 87 is also rotated, and through the rock-shaft 90 and ball-and-socket connections described will rotate the shaft 103 to bring the head 133 in proper position with relation to the index-plate 134, which position, when the mortises are to be diametrically opposite as in this case, will 110 correspond with the original position. The mechanism associated with the chuck and coöperating with the index-plate 134 insures the proper relative positioning of the pulley-rim and cutter-chain head, therefore 115
120
125
130

after simple adjustments above described and requiring little mental calculation have been made, the treadle and rod 103 may be depressed to set the machine in action for a repetition of the mortising operation on the ply h of said rim in the manner before described, after which the parts will be again locked in position and the mortising will proceed as aforesaid until every alternate ply has been mortised, the tool-head being fed back by the same gradations by which it was fed forward simply by reversing the direction of rotation of the hand wheel 152. Properly to locate the slide 52, the rotatable chuck thereon, and the arm 64 attached to said chuck should it be desirable to change the location of the mortises in the pulley-rim the pull-rod 81 is withdrawn by knob 84, and the tubular shaft 55 is turned by the hand-wheel 80 to actuate the pinion 55', and thereby adjust said slide transversely of the slide 47, this adjustment being limited in either direction by the set-screws 61 heretofore described.

In its descent the movement of the slide 47 is limited by the engagement of the head 105 with the stop 126 which will depress the rod 103 and attached parts against the action of the spring 120, thereby throwing down the treadle and the shifting-dog 108, actuating the clutch to a neutral position and thus stopping the machine. It will be seen from the above description that by the means described the proper positioning of the cutter-chain for forming the mortises in any desired plies of the pulley-rim is positively controlled by a mechanical index which may be made to regulate the location of the mortising-cuts that can be made according to the different rotative positions to which the pulley-rim may be adjusted under the cutter-chain, it being impossible to depress the treadle unless the parts of the indexing-mechanism are in accurate relation for the mortise required.

To compensate for wear of the face of the cam 87 a slip-adjustment as regards the part 98 and the ball-and-socket mechanism is provided, to furnish ready means for readjusting the devices to conform to the changed conditions while the spring 129 (Fig. 2) serves to take up all slack or lost-motion, and to retain the arm 89 and its roller 88 in contact at all times with the face of the cam. When working on pulley-rims of narrow width of face the slide 237 is utilized to stop out the necessary holes 235 in the index-plate 134, as illustrated in Fig. 23.

In virtue of the construction described 50 pulley-rims of any diameter, or of any width of face, and composed of any desired number of plies may be accurately mortised, and after all of the mortises have been formed in a pulley-rim, said mortises opposing each other as stated, the rim is sawed

apart on the line 247 and the spoke or spokes may be secured in position in the manner stated.

While the pitch of the screw 43 the proportions of the gearing and index have all been designed for a fixed thickness of the mid-plies of pulley-rims, variations in the width of the pulley-face from even multiples of the standard mid-ply are secured by varying the inner and outer edge-ply thicknesses. It is, however, obvious that the machine can be so made or changed as to accommodate any width of mid-ply, and also to position the mortises in or out of the center of each ply or of alternate plies as desired, and it is distinctly to be understood that the invention is not limited in this respect, nor in respect to the number of mortising positions or the number of spokes or arms, or a series of said spokes or arms. 75

While the chuck-slide is adapted to be raised and lowered by a screw with a trapezoidal thread having a flat surface on its top, said screw being driven by spiral-gears at the bottom, and said gears running in an oil-bath, the invention is not limited to this mode of actuating the slide, for other devices may be substituted therefor, without departure from the invention. 90

By placing the tool in any of the sockets 28 of the eccentric-bushing 27, and then rotating said bushing the spiral gear 29 may be withdrawn from intermeshing engagement with the mating spiral-gear 36. 95

As will be observed, the sprocket shaft or 100 spindle 168 slides through the bushing 171 rigid with the belt-pulley 173, and a balanced driving-effect is produced by the two feathers 170 on the opposite sides of said shaft or spindle.

To avoid wear on the shaft 168 the pulley 173 is mounted to rotate on the stationary sleeve 174, and the shaft 168 readily slides through said sleeve and is protected by a shield as stated. As the height of the machine makes it necessary to be able to regulate the chain-tension by a hand-wheel 209 and its connections a platform 260 is provided on the base 2, on which platform the operator may stand, and thus readily reach 110 the tension adjusting-mechanism.

In the present machine new conditions as regards the cutter-chain take-up or tension devices are encountered, this being due to the width of the base of the material being 120 operated upon. Consequently, any adjustment of the block or cross-head 191 to take up the slack of the chain must bring said block below the apron or hanger 193 so that the work will not collide with the same. 125

Changes may be made in numerous details of the machine without departure from the invention, and while shown designed for mortising pulley-rims the invention is not limited to any specific use, for many of its 130

details and combinations of coacting parts may be utilized in other relations without departure from the invention. So too, the invention is not limited to the specific indexing-mechanism illustrated and described, nor is it limited to belt-gearing illustrated for driving the feed-mechanism from the cutter-actuating spindle.

While a chain-cutter is shown for accomplishing the mortising-operations, other kinds of mortising-cutters, and other kinds of mechanism for driving said cutters, may be employed as substitutes therefor, if desired.

Any form of clutch may be used for coupling either pulley 20 or 21 to the shaft 19, and various kinds of clutch-shifting mechanism may be employed as substitutes for that described.

Having thus described my invention, what I claim is—

1. The combination, with a work-support, of a driving shaft; a driven shaft at one side of the driving-shaft; a clutch splined to and movable on the driven shaft; a cutter; a cutter-actuating spindle; means operated by the driving-shaft for actuating said spindle; elements loose on the driven shaft, and with either of which the clutch may be engaged; means for operating one of said elements from the driving-shaft; means for driving the other of said elements from the cutter-spindle; and means operated by said driven-shaft for operating the work-support.

2. The combination, with a driving-shaft, of belt-pulleys rigid therewith; driven shafts, one at each side of the driving shaft; a tool actuated by one of said driven shafts; a belt-pulley loose on the driving-shaft; a belt connecting said loose pulley with the tool-operating driven shaft and a belt connecting one of the pulleys rigid with the driving shaft with said tool-operating shaft; belt-pulleys loose on the other driven shaft; a crossed-belt connecting one of said loose pulleys with the loose pulley on the driving-shaft; a belt connecting one of the pulleys rigid with the driving-shaft with the other loose pulley on said driven shaft; a clutch splined to, and movable on said driven shaft and engageable with either of the loose pulleys on said shaft; a work-support; and means operated by the driven shaft when either loose pulley is connected thereto by said clutch for actuating the work-support.

3. The combination, with a slide, and with a screw for operating the same, of a star-wheel and pin-wheel motion for actuating said screw; an index-plate carried by the slide; means actuated by the star-wheel and pin-wheel motion for locking and releasing the index-plate; a mortising-tool movable with the slide; a work-support; and means controlled by adjustment of an element of

said work-support for operating an index co-operating with the index-plate to determine correct correlative adjustment of said element of the work-support and of the tool slide.

4. The combination, with a slide, and with a screw for operating the same, of a star wheel and pin-wheel motion for actuating said screw; an index-plate carried by the slide; means actuated by the star-wheel and pin-wheel motion for locking and releasing the index plate; a mortising-tool movable with the slide; a work-support; means controlled by adjustment of an element of said work support for operating an index co-operating with the index-plate to determine correct correlative adjustment of said element of the work-support and the tool-slide; and means for advancing and withdrawing said work-support.

5. The combination, with a sliding-head, of a mortising tool carried thereby; an index-plate movable with the head; means for actuating the sliding-head comprising a star-wheel and pin wheel movement; and a device for locking and releasing the index-plate to and from the sliding head, said device being actuated by the star and pin wheel movement.

6. The combination, with a sliding-head, of a mortising tool carried thereby; an index-plate movable with the head; means for actuating the sliding-head comprising a star-wheel and pin wheel movement; and a device for locking and releasing the index-plate to and from the sliding head, said device being actuated by the star and pin wheel movement; a work-support; an index actuated by adjustment of a part of said work-support; and means for advancing and retracting said work-support.

7. The combination, with an index-plate having a longitudinal slot, and notches or seats on each side of said slot; an index co-operating with the indexing-plate, and passing through the slot thereof; a work-support; means controlled by adjustment of said work-support for operating said index; means for locking and releasing said index-plate; a star-wheel and pin-wheel motion, an element of which actuates said means; a tool-carrying slide rigid with the index-plate; and means controlled by said star-wheel and pin-wheel motion for actuating said slide.

8. In a mortising machine, the combination, with a rod having a chambered block secured to the end thereof; a chip-breaker comprising a stick, and a flanged metallic arm secured in the opening of the block; and means for compressing the arm against the stick.

9. The combination of a mortising device, a work-support and a carriage, one of which two latter parts supports said mortising device and is also movable with respect

to the other to bring the mortising device opposite different portions of the work, an index-device coöperative with said carriage, mechanism for causing the mortising device to enter the work, and a hand-operable device for throwing said mechanism into action, the index device having separated apertured portions for the passage of said hand-operable device when there is a predetermined relation between the carriage and work-support.

10. The combination of a mortising-device, a work-support and a carriage, one of which latter two parts supports said mortising device and is also movable with respect to the other to bring the mortising device opposite different portions of the work, an index-device coöperative with said carriage, mechanism for causing the mortising device to enter the work, and a hand-operable device for throwing said mechanism into action, the index device having separated series of apertures and the hand-operable device having a part to enter the apertures of the respective series and being oscillatory for such purpose and said series being staggered with respect to each other.

11. The combination of a mortising device, a carriage and a work support, said two latter parts having a compound relative movement and the mortising device being supported by the carriage, whereby said mortising device may be brought opposite different portions of the work in transverse directions to form staggered mortises therein, mechanism for causing the mortising device to enter the work, a hand-operable member for throwing said mechanism into action, and an index device for preventing a full stroke of said hand-operable member unless there be a predetermined relation between the carriage and work-support.

12. The combination of a sprocket-wheel, a chain driven by said sprocket-wheel and provided with mortising teeth, a bar provided with guiding means for said chain, a block to which said bar is attached, and a

bearing to which said block is connected for adjustment in the direction of the movement of said chain to thereby regulate the tension of said chain, said block having side standards rigidly connected therewith straddling and having a bearing engagement against said bearing.

13. The combination of a sprocket-wheel, a chain driven by said sprocket-wheel and provided with mortising teeth, a bar provided with guiding means for said chain, a block to which said bar is attached, and a bearing provided with a grooved hanger in the groove of which said block is slidable to thereby regulate the tension of said chain, said block having a pair of side standards straddling and having a bearing engagement against said bearing.

14. A head having a stick-receiving chamber, a stick-engaging plate extending through the chamber on the outer side thereof, provided at its forward end with a chute, and means for holding the plate in place.

15. A head having a stick-receiving chamber, a stick-engaging plate extending into said chamber, provided with a chute, said plate having means for engaging the stick on two distinct surfaces one on the outer side of said stick, and means for holding said plate in position.

16. The combination of mortising mechanism, a head supported in coöperative relation with said mortising mechanism, an adjustable member supporting the mortising mechanism and said head, a flanged metallic arm, the head having a chamber through which said arm passes said arm having a chute at one end thereof, and a screw tapped through the outer side of said head for holding said plate in place.

In testimony whereof I affix my signature in presence of two witnesses.

ROBERT S. BROWN.
